COASTING DEVICE

Allen M. Flanders and Joseph T. Dessureau,
Barre, Vt.

Application March 21, 1939, Serial No. 263,242

3 Claims. (Cl. 280—16)

The invention aims to provide a rather simple and inexpensive, yet a very desirable coasting device of novel construction to yieldably support the rider's weight.

5 A further object is to provide a novel runner construction which may be easily and inexpensively manufactured from sheet metal, yet will be strong and durable and will prevent side slip on soft snow, snow crust and ice.

19 With the foregoing and minor objects in view, the invention resides in the novel subject matter hereinafter described and claimed, description being accomplished by reference to the accompanying drawing.

15 Figure 1 is a side elevation.

Figures 2, 3, 4 and 5 are detail sectional views on lines 2—2, 3—3, 4—4 and 5—5 of Figure 1, respectively.

A preferred construction has been illustrated 20 and will be rather specifically described, with the understanding, however, that within the scope of the invention as claimed, variations may be made. Moreover, while we have shown the device as provided with supporting members in the form of runners for use on snow and 25 ice, it is well within the scope of the invention to provide supporting members in the form of wheels for use upon sidewalks, roadways and the like, if desired.

30 Over the front and rear members 10 and 11, is a longitudinally arched bar 12 which is preferably formed from spring steel, the rear end of said bar being connected at 13 with the rear supporting member 11. The front end of the 35 bar 12 is formed with an opening 14 through which a steering post 15 passes rotatably, the lower end of said steering post being connected at 16 with the front supporting member 10. The upper end of the post 15 is provided with handle 40 bars or the like 17 and provision is preferably made for adjusting them vertically, for instance, by providing the bolt 18 and the adjusting openings 19. A second longitudinal bar 20 which is also preferably formed from spring steel, is secured between its ends upon the upper portion 45 of the bar 12, by means of rivets or the like 20'. A seat 22 is secured upon the rear portion of this bar 20, and the front end of said bar is formed with an opening 21 through which the steering post 15 extends. Cotter pins 22 are shown passing through the post 15 above and below the spring bar 20 to hold the latter against appreciable vertical sliding upon the post. Stops 50 23 have also been shown on said post under the front end of the spring bar 12 to support the

latter against downward sliding on said post. The stops 23 may well be formed by heads of a rivet 24 which secures a plug 25 in the lower end of the post 15, said plug being formed on the upper end of a small vertical plate 26 which is 5 instrumental in connecting the lower end of the post with the front supporting member 10. The rear end of the bar 12 is preferably given a quarter twist 27 to dispose it in a vertical longitudinal plane to aid in establishing the connection 13 between said bar and the rear supporting member 11. The front and rear connections 13 and 16 will be hereinafter explained more fully after a description of the supporting members 10 and 11. As these members are duplicates in 15 the present disclosure, a description of one will suffice, the member 10 being selected.

An elongated sheet-metal runner plate 28 is provided having an upwardly curved front end 29, the longitudinal edges of said plate being 20 bent downwardly at obtuse angles as shown at 30 to prevent side slip on snow crust and ice. Plate 28 is also provided with a central longitudinal upwardly stamped portion 31 providing the lower side of said plate with a groove to prevent 25 side slip on soft snow. Two parallel vertical gussets 32, formed from sheet metal, are disposed longitudinally over the runner plate 28 and at their lower edges contact with the upwardly stamped ridge 33 which provides the 30 groove 31, said lower edges of said gussets being bent laterally outward to provide flanges 34 which are secured by rivets 35 or by any other suitable means upon the plate 28, not only securely mounting the gussets 32 but reinforcing 35 said plate 28. The front and rear ends of the gussets 32 are preferably inclined and their edges are provided with inwardly stamped portions 36 which are welded or otherwise secured together, holding said gussets in rigid spaced relation and 40 providing for a strong structure with light material.

The plate 26 or the rear end of the bar 12, as the case may be, extends downwardly between the two gussets 32 and is formed with an opening 37 receiving a spacer 38 which contacts with the inner sides of said gussets and is secured in place by a bolt 39, providing an effective pivot which allows vertical oscillation of the runner or ski.

50 We preferably provide a transverse foot bar 40 to support the user's feet, and a suitable clamp 41 is provided for securing this foot bar upon any desired portion of the longitudinally arched bar 12. In the present showing, the clamp 41 is en- 55

gaged with the front extremity of the bar 12, in advance of the steering post 15, but said clamp may well embrace any other portion of said bar 12 to position the foot bar 40 for the user's convenience.

It will be seen that the entire structure is relatively simple and inexpensive, yet that it will be very desirable and will give a great deal of enjoyment. When one or both of the bars 12, 20 10 is/are formed from spring metal, sufficient yielding will occur in use to prevent the user from being uncomfortably jolted. Moreover, when bar 20 is formed from spring metal, the rear portion of this bar yieldably supports the seat while the 15 front end of said bar is yieldably supporting the frame structure. Even if one or the other of the bars 12, 20 be inherently rigid, the other of these bars will resiliently mount the frame upon the steering post, but when either bar is rigid, its 20 front end must of course be so connected with the steering post that it may slide thereon during yielding of the other bar.

Excellent results have been obtained from the details of construction shown and described and 25 they are, therefore, preferably followed. However, attention is again invited to the possibility of making variations within the scope of the invention as claimed.

What is claimed is:

30 1. In a coasting device, an elongated sheet metal runner plate, and two parallel vertical sheet metal gussets over the central longitudinal portion of said runner plate and having horizontal outwardly projecting flanges at their lower edges secured 35 upon said runner plate, said gussets being spaced apart to receive a frame member therebetween and having inwardly stamped upper edge portions secured to each other.

2. A coasting device comprising front and rear 40 runners each having a pair of upwardly projecting laterally spaced plates, a longitudinally arched one-piece spring bar of flat cross section, the rear

end of said spring bar being pivoted between said plates of the rear runner, the front end of said spring bar being directed forwardly and having a circular opening above said plates of the front runner, a second spring bar of flat cross section rigidly secured between its ends upon the crown portion of said arched spring bar, the rear end of said second bar being curved upwardly from said crown portion and provided with a seat, the front portion of said second spring bar being directed 10 forwardly and having a circular opening above the aforesaid circular opening, a vertical steering post passing rotatably through said two circular openings and having a flat lug on its lower end pivoted between the aforesaid plate of said front runner, the upper end of said steering post being provided with means whereby it may be turned, and projecting means fixedly carried by said steering post and underlying the front ends of both of said spring bars.

3. In a coasting device, an elongated one-piece sheet metal runner plate having its central longitudinal portion stamped upwardly to provide a longitudinal snow groove in the bottom of the plate and a longitudinal reinforcing ridge on the 25 top of said plate, said plate having its longitudinal edges bent downwardly to provide snow-crust-and-ice-engaging-flanges which further reinforce said plate, and two horizontally elongated parallel vertically positioned sheet metal plates at opposite sides of said ridge and having outwardly bent reinforcing-and-attaching-flanges on their lower edges, said flanges being secured upon said runner plate, said two vertical plates having upper edges which decline to the front and rear 35 ends thereof, said declined edges of said two vertical plates having inwardly bent elongated plate-spacing-and-reinforcing-portions secured to each other.
